(57) **CLAIM**

The ornamental design for a storage unit for electronic devices, as shown and described.

DESCRIPTION

FIG. 1 is a top front left-side perspective view of a storage unit for electronic devices showing my new design;

FIG. 2 is a top rear right-side perspective view thereof with door panels of the storage unit in an open position;

FIG. 3 is a top plan view thereof;

FIG. 4 is a bottom plan view thereof;

FIG. 5 is a left-side view thereof, the right-side being a mirror image thereof;

FIG. 6 is a front end view thereof;

FIG. 7 is a rear end view thereof; and,

FIG. 8 is a top left-side perspective view thereof with the doors of the storage unit in the open position.

The features shown in broken lines in the drawing figures are environmental structure that form no part of the design to be patented.
